UNITED STATES PATENT OFFICE

2,608,740

CONTINUOUS FURNACE

Elmer W. Dany, Brecksville, Ohio, assignor to
Ferro Corporation, a corporation of Ohio

Application July 26, 1950, Serial No. 175,912

3 Claims. (Cl. 25—142)

1

This invention relates as indicated to continuous furnaces and has more particular reference to U or hairpin conveyor type continuous furnaces for porcelain enameling.

Hairpin type continuous conveyor furnaces, for porcelain enameling, as now constructed are provided with a slot in the roof through which the conveyor means travels. The ware to be porcelain enameled is attached by various types of burning bars to the conveyor and is thus moved through the furnace. This type of furnace is subject to dirt and foreign matter falling through the slot in the roof and thereby contaminating the ware.

The present invention seeks to remedy this defect by providing a continuous conveyor type furnace with a slot in the bottom thereof.

It is therefore the principal object of the present invention to provide a bottom slot continuous furnace and a conveyor means therefore.

Other objects will become apparent as the description proceeds.

To the accomplishments of the foregoing and related ends, the invention then, comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said drawings:

Fig. 1 is a horizontal longitudinal diagrammatic view of a continuous bottom slot furnace;

Fig. 2 is a transverse cross sectional view of the front of the furnace;

Fig. 3 is a transverse cross sectional view taken through line 3—3 of Fig. 1; and

Fig. 4 is a cross sectional view showing the conveyor means in detail.

Referring to the drawings I show a furnace 1 which is closed at the top and has a slot in the bottom and which may be constructed of suitable materials such as firebrick and the like according to well known principles. The furnace comprises essentially a burning chamber 2 and a preheating and cooling chamber 3. Suitable ports or doors 4 and 5, being only large enough to receive ware with appropriate carriage, are provided at the front end of the furnace, the back end of the furnace being closed.

The conveying system for carrying the ware into and out of the furnace, is located at the bottom of the furnace and extends upwardly into the furnace through a continuous slot 15 provided

for the purpose and comprises essentially an endless chain 6 supported by guide rail 7. A plurality of horizontally disposed supporting members 8 are connected to chain 6. The free end of supporting member 8 terminates in a downwardly extending idler wheel 9 which travels on idler track 10. Ware carrying members 11 are mounted substantially in the center of supporting means 8. The chain is moved in a horizontal motion by any of the well known mechanical means (not shown here).

Carried and supported by collar 12 on the supporting means 8 is a continuous articulated shield 13 which comprises shoe plates, slidably engaging tracks 14. Tracks 14 comprise a pair of angle irons which slightly overhang the front of the furnace and are declined slightly to receive the shoe plates.

The ware is loaded and unloaded at the front door end of the furnace near the doors 4 and 5, the unfired ware enters through door 5 and progresses through the preheating and cooling chamber 3 to the burning chamber 2, where it is carried through a 180° arc and returned through the preheating and cooling chamber 3 out of the door 4 where it is unloaded. The ware is of course completely fired in the burning chamber and it is my intention that after leaving the burning chamber it delivers up heat to the incoming unfired ware. Preferably the preheating and cooling chamber is about twice as long as the burning chamber.

Since it is not necessary to maintain a high temperature in the preheat zone 3 I have found that the furnace can be constructed more economically by eliminating the bottom layer of insulation, as shown at 16 in Fig. 2. However, in the heating zone area where it is important to maintain a high and substantially constant temperature the area 17 beneath the heating elements 18 is completely insulated.

The foregoing has described my furnace in a general way and has particularly dealt with the means for conveying ware through the furnace. While I have illustrated the present furnace as being heated by electricity, I wish it to be understood that it is entirely within the contemplation of the present invention to include various other means of firing the furnace.

From the foregoing description it can now be readily seen that I have provided a U type continuous furnace with a bottom slot. The furnace having a closed roof is absolutely impervious to dirt, etc., from falling on the ware going through the furnace. Furthermore, I have pro-

vided a conveying means for said bottom slot furnace and means preventing an ingress of cold air through the bottom. The furnace of my invention is more efficient than present type top-slot furnaces since the roof is closed and there is less loss of heat due to the slot in the roof.

Other modes of applying the principle of the invention may be employed, change being made as regards the details described, provided the feature stated in any of the following claims or the 10 equivalent of such be employed.

I, therefore, particularly point out and distinctly claim as my invention:

1. The combination with a U-type furnace of a continuous conveyor for carrying ware through said furnace comprising a guide rail located at the bottom and substantially to one side of the center of said furnace, an endless horizontal chain supported by said guide rail, means for imparting horizontal motion to said chain and the free 15 ends of such supporting members terminating in a downwardly extending idler wheel, a track disposed beneath said idler wheel and an upwardly extending ware carrying member mounted substantially in the center of each of said supporting means, and means for preventing ingress of cold air through said continuous opening, said last named means comprising overlapping plates engaged by said ware carrying members and slid able along tracks, said plates being 20 solely supported by said tracks while in the furnace and by said ware carrying members when outside of the furnace.

2. A furnace comprising a preheating and cooling chamber, a burning chamber located at one end of said preheating and cooling chamber, means for conveying articles through said chambers through a continuous slot provided in the bottom of said chambers whereby said articles are conveyed into and from said preheating and cooling chamber in substantially parallel adjacent paths, said conveying means comprising a 45 guide rail located at the bottom and substantially to one side of the center of said furnace, an endless horizontal chain supported by said guide rail, means for imparting horizontal motion to said chain, a plurality of horizontally disposed sup- 50

porting members mounted on said chain and the free ends of said supporting members terminating in a downwardly extending idler wheel, a track disposed beneath said idler wheel and an upwardly extending ware carrying member mounted substantially in the center of each of said supporting means, and means for preventing ingress of cold air through said continuous opening, said last named means comprising overlapping plates engaged by said ware carrying members and slid able along tracks, said tracks disposed above said horizontal chain and above said idler track, said plates being solely supported by said tracks while in the furnace and by said ware carrying members when outside of the furnace.

3. A porcelain enameling furnace for continuously firing work conveyed therethrough comprising an elongated tunnel provided with a longitudinally extending slot in the floor thereof and means for conveying ware through said slot, said means comprising a hollow channel guide rail located below and substantially to one side of the center of said slot, a plurality of horizontally disposed supporting members mounted in said hollow channel and means interconnecting said supporting members whereby such supporting members may be moved in unison through said slot, the free ends of said supporting members terminating in a downwardly extending wheel, a track disposed beneath said idler wheel and an upwardly extending ware carrying member mounted substantially in the center of each of said supporting means.
